(57) **CLAIM**

The ornamental design for a display screen with graphical user interface, as shown and described.

DESCRIPTION

FIG. 1 is a front view of a display screen with graphical user interface, according to a first embodiment of the invention. FIG. 2 is a front view of a display screen with graphical user interface, showing the design of FIG. 1 in a different environment.

FIG. 3 is a front view of a display screen with graphical user interface, showing the design of FIG. 1 in a different environment.

FIG. 4 is a front view of a display screen with graphical user interface, showing the design of FIG. 1 in a different environment.

FIG. 5 is a front view of a display screen with graphical user interface, showing the design of FIG. 1 in a different environment.

FIG. 6 is a front view of a display screen with graphical user interface, according to a second embodiment of the invention.

FIG. 7 is a front view of a display screen with graphical user interface, showing the design of FIG. 6 in a different environment.

FIG. 8 is a front view of a display screen with graphical user interface, showing the design of FIG. 6 in a different environment; and,

FIG. 9 is a front view of a display screen with graphical user interface, according to a third embodiment of the invention. The features shown in broken line show portions of the graphical user interface that form no part of the claimed design.
